W. SPARKS.

VACUUM TANK,

APPLICATION FILED FEB. 18, 1919.

1,343,591.

Patented June 15, 1920.

19 William Sparks INVENTOR

BY *Leinson Thompson*
ATTORNEYS.

UNITED STATES PATENT OFFICE.

WILLIAM SPARKS, OF JACKSON, MICHIGAN.

VACUUM-TANK.

1,343,591.

Specification of Letters Patent. Patented June 15, 1920.

Application filed February 18, 1919. Serial No. 277,794.

To all whom it may concern:

Be it known that I, WILLIAM SPARKS, a citizen of the United States of America, and resident of Jackson, in the county of Jackson, in the State of Michigan, have invented new and useful Improvements in Vacuum-Tanks, of which the following, taken in connection with the accompanying drawings, is a full, clear, and exact description.

10 This invention relates to certain improvements in liquid feeding devices commonly known as vacuum tanks, designed for use, particularly in supplying liquid fuel to internal combustion engines of automobiles, and the like, in connection with which it is very often desirable to have the primary fuel tank carried on the vehicle at a level below the carbureter.

15 The object of the invention is to provide a device of relatively simple construction and high efficiency in automatic operation, and to which the liquid fuel is elevated as by the suction of the engine and from which the fuel may be continuously charged to be fed by gravity to a vaporizing device as for instance to the float chamber of a commercial carbureter.

20 The important feature of improvement in the combination named is the under liquid normally open valve between the two chambers of the vacuum tank, so that when the suction starts in the upper chamber, the valve between the two chambers is immediately closed without the passage of air from the lower to the upper chamber, which passage of air, if it should take place, would tend to produce vacuum in the lower chamber and in the carbureter, and to neutralize 25 the vacuum in the upper chamber. The under liquid condition of this valve is the very essence of this invention broadly considered.

25 In the drawings I have illustrated two structural methods of accomplishing this object.

Figure 1 is a sectional elevation of a vacuum tank embodying the features of this invention.

30 Fig. 2 shows a modified structural means of communication between the two chambers.

Fig. 3 is a cross-section on line 3-3, Fig. 1.

35 As stated the device is especially designed for use in connection with automobiles em-

bodying internal combustion engines, the vacuum tank portion thereof may be positioned at any point upon the vehicle to automatically supply fuel to the carbureter, as by gravity, and in practice is positioned some distance above the carbureter and above the primary fuel tank.

40 As shown, the invention comprises the tank —1— having suitable connection through a pipe —2— with a primary fuel tank, (not shown), a second connection as through pipe —3— with any source of suction, as the manifold (not shown), of an engine and a third connection as through pipe —4— with a carbureter (not shown).

45 The tank —1— is formed of a sheet metal tubular body portion —5— preferably cylindrical in form and having its lower end closed by wall —6— and divided into two chambers —7— and —8— by an annular transverse wall —9—, having an axillary extending flange —10— tightly fitting within the tubular body portion and secured thereto in any suitable manner as by soldering or the like. The transverse wall —9— is provided with a central opening within which is fitted a flanged circular bushing —11— which may, as shown, be internally threaded for the reception of an externally threaded portion —12— upon a discharge nipple —13—, having a materially enlarged portion —15— at its lower end to permit the rapid discharge of fluid, when the valve —16— opens upon partial neutralization of the vacuum in chamber —7—. The valve —16— is preferably supported in an angular position with reference to the substantially horizontal downwardly facing valve seat formed by the lower end of nipple —13—, and this is accomplished by means of a series of angular fingers —17—, in this instance, three in number, spaced substantially equidistant from each other, and one of the same projecting a materially shorter distance below the nipple —13— than the other two. The nipple —13— may, as shown in Fig. 1, project only a short distance into the upper portion of chamber —8—, and for the purpose of keeping the valve —16— at all times immersed in liquid, a cup like structure —18— is shown inclosing the nipple —13— and suitably supported, as by securing to the cross wall —9— either by rivets or otherwise. This cup like member —18— is provided with a discharge opening or openings —19—, some

distance above the lower termination of nipple —13—. These openings should be of sufficient number and sufficient size to permit rapid escape of all liquid that can be conveyed by nipple —13— and discharged from the same when valve —16— is open.

In Fig. 2, I have disclosed a modified form of normally open under liquid valve in which the nipple —13— is replaced by an 10 elbow shaped nipple 13' discharging laterally and having a valve seat inclined downwardly away from the vertical plane passing through its upper position, so that valve 16' loosely carried by studs extending 15 outwardly from the nipple, normally by gravity seeks an open vertical position, permitting free escape of the liquid in the upper chamber; but due to its under liquid condition closing immediately upon the production 20 of vacuum in the upper chamber.

The bushing —11— may support a spider —19—, having a passage-way alined with nipple —13— for the reception of valve stem —20— carrying valve —21— for closing the 25 passage-way —22— permitting communication between chamber —7— and pipe —3—. The operation of valve —21— is controlled by float —23— positioned within the chamber —7— and mounted upon and rigidly secured to valve stem —2—.

The pipe —3— may be secured to cover plate —24— in any suitable manner as by coacting threads and for the purpose of rigidly securing the cover —24— to the tubular body —5—, a ring-shaped angle bar —25— preferably formed of sheet metal with one of its walls —26— formed of one thickness of the sheet metal telescoped externally with the body and its other wall 40 —27— of two thicknesses of the sheet metal extending radially and inwardly of the body —5— to form a seat for packing —28— upon which the cover plate rests. The cover plate may be secured to the angle bar as by 45 screws —29—, extending through the plate into the bar. The nipple —30—, to which the pipe —2— is secured is likewise connected to engagement with flange —31— formed upon the cover plate.

50 An air inlet conduit —32— communicates with the chamber —7— through the cover —24— and may be secured thereto in any suitable way as by coacting threads.

A disk —33— may be provided secured 55 to the inner face of the cover plate for forming a seat for an inwardly closing valve —34— controlling a communication between the conduit —32— and chamber —7—. This valve is actuated by springs 60 —35— and —36— each having one end moving with the float, the other end of spring —35— connecting to lever —37— pivotally secured to the cover plate, the other end of spring —36— connected to flange —38—, 65 projecting downward from the cover plate.

The construction and operation of this portion of the device is substantially the same as that disclosed in Letters Patent Number 1,255,347, issued to me February 5, 1918.

70

The operation of the apparatus herein described will be readily understood without the necessity of further description.

Although I have shown and described a specific construction as illustrative of my 75 invention and the appurtenances in connection with which the same may be used, I do not desire to limit myself to the same as various changes may be made in the details of construction without departing 80 from the spirit of this invention as set forth in the appended claims.

What I claim is:

1. In a device of the class described, an upper chamber having an air exhaust, an air inlet and a fuel inlet, a second chamber, having a fuel discharge, a partition wall separating said chambers, a nipple depending from said partition wall and forming a means of communication between said 90 chambers, a valve controlling the discharge of fuel from said nipple into said second chamber, and a cup-like member surrounding said nozzle and secured at its open end to said partition wall, and having a discharge for fuel located above said valve.

2. In a device of the class described, an upper chamber having an air exhaust, an air inlet and a fuel inlet, a second chamber, having a fuel discharge, a partition wall 100 separating said chambers, a nipple depending from said partition wall and forming a means of communication between said chambers, a valve controlling the discharge of fuel from said nipple into said second 105 chamber, and a cup-like member surrounding said nozzle and secured at its open end to said partition wall, and having a discharge for fuel through its side wall above said valve.

110

3. In a device of the class described, an upper chamber having an air exhaust, an air inlet and a fuel inlet, a second chamber, having a fuel discharge, a partition wall separating said chambers, a nipple depending from said partition wall and forming a means of communication between said chambers, a normally open valve controlling the discharge of fuel from said nipple into said second chamber, and a cup-like member 115 surrounding said nozzle and secured at its open end to said partition wall, and having a discharge for fuel located above said valve.

120

In witness whereof I have hereunto set my 125 hand.

WILLIAM SPARKS.
